UNITED STATES PATENT OFFICE

VERNER RUSSELL CHADWICK, OF LONDON, ENGLAND

CHAIN GRATE STOKER

Application filed April 3, 1929, Serial No. 352,297, and in Great Britain May 3, 1928.

This invention is for improvements in or relating to chain grate stokers for steam-boilers or other furnaces of the type wherein the air for combustion is supplied under pressure, being for example induced by steam-jets or by blowers, in the usual manner.

One object of the invention is to improve generally the construction of stokers of the aforesaid type, whereby more perfect combustion of the fuel can be obtained with a view to ensuring smokeless operation of the furnaces.

According to one feature of the present invention an air-duct is provided at each side of the chain grate and each of these air-ducts extends longitudinally of the grate approximately from end to end thereof. Moreover, each duct has a wall arranged in close proximity to the grate so as to form a side wall for the latter, each of these side walls extending from the upper run of the grate to about the level of the lower run thereof.

In a convenient construction, the air-passage aforesaid extends substantially throughout the length of the grate in proximity thereto and is divided into two separate ducts arranged horizontally one above the other and in communication with one another at the rear end of the furnace, and means are provided at the front end of the furnace for admitting air to one duct, which air flows along said duct to the rear end of the furnace and returns along the other duct to the front end of the furnace where it enters said transverse chamber. Preferably, air is admitted to the lower duct and returns along the upper duct so that the air is gradually heated during its passage to the grate.

According to another feature of the invention, a chain grate stoker constructed as described in either of the two preceding paragraphs, comprising a plurality of air-troughs, and wherein the grate is composed of a plurality of links which are interconnected by means of pins passing through holes in lugs on said links may be provided with rollers which are mounted on said pins between adjacent links at intervals trans-

versely of the grate and are adapted to run on the upper edges of the sides of the air-troughs aforesaid.

Other features of the invention will be apparent from the following description of one specific embodiment thereof, which will now be described by way of example, with reference to the accompanying drawings, in which—

Figure 1 is a longitudinal section of a furnace on the line 1—1 of Figure 2 with a chain grate stoker according to the invention applied thereto;

Figure 2 is an end elevation, partly in section, on the line 2—2 of Figure 1, and in part diagrammatic;

Figure 3 is an enlarged side elevation of the rear end of the chain grate;

Figure 4 is an elevation, partly in section, on the line 4—4 of Figure 3, drawn to a still larger scale;

Figure 5 is a section on the line 5—5 of Figure 4, drawn to the same scale as Figure 3;

Figure 6 is a perspective view of one of the links of the chain grate, and

Figure 7 is a similar view of a link constructed to accommodate the rollers aforesaid.

Like reference numerals indicate like parts in the various figures of the drawings.

The chain grate is mounted on a unitary frame-structure which comprises at each side of the grate two air-ducts 10, 11, which extend substantially throughout the length of the grate in proximity thereto and are arranged horizontally one above the other. The partition 12, separating the ducts of each pair, terminates a short distance from the rear end 13 of the frame-structure to provide an opening 14 through which air can flow from the duct 10 into the duct 11. Each of the ducts 11 communicates at the front end of the grate with a transverse air-chamber 15. The rear wall of this air-chamber is provided with apertures 16 that communicate with six longitudinally arranged air-troughs 17, which are disposed beneath the upper run of the grate, and are integral with, or secured to, the air-chamber afore-

said. Each of the air-troughs diminishes in cross-sectional area towards its rear end, thus assuring an even flow of the air for combustion. The air-troughs 17 are supported on transverse bars 18 carried by brackets 19 secured to the inner walls of the air-ducts 10. Air is admitted to the front ends of the ducts 10 through injectors 20 provided with draught-inducing steam-jets 21. It will be appreciated that the air induced into the ducts 10 flows therealong to the rear end of the furnace whence it enters the ducts 11, along which it flows, into the transverse air-chamber 15 and thence into the troughs 17. In order to ensure a satisfactory flow of the air, auxiliary steam-jets 22 are provided in the chamber 15 adjacent the ends of the troughs 17.

The chain grate is composed of a plurality of links which are interconnected by means of pins 23 passing through holes in lugs 24 on said links. Rollers 25 are mounted on the pins 23 between adjacent links at intervals transversely of the grate, which rollers run on the upper edges of the sides of the troughs 17. On reference to Figure 2, it will be seen that in the construction illustrated, three sets of rollers 25 are provided. The chain grate passes around polygonal drums 26, 27, at the front and rear ends respectively of the grate, which drums are carried by shafts mounted in suitable bearings in the walls of the air-ducts 10 and 11. Rollers 25 are so arranged longitudinally of the grate that each in turn will engage between adjacent teeth of appropriately disposed sprocket-wheels 28, 29 on the drums 26, 27 respectively.

The chain grate is slowly moved through the furnace by rotating the shaft 30 on which the drum 26 is mounted. This rotation may be effected by means of a worm-wheel 31 on the shaft 30, which worm-wheel meshes with a worm 32 on a shaft 33 that can be rotated by any convenient mechanism in the usual manner.

The links of the chain grate may be of any convenient construction which will permit air to pass between them from the troughs 17 to the fuel above. In the construction illustrated in the drawings, each link is provided on each side with inclined ribs 34 which are spaced apart so as to provide air-passages 35 between them. These ribs 34 are so arranged that in the upper run of the grate the said air-passages slope upwardly towards the rear end of the furnace. It will be appreciated that owing to the inclination of said ribs they intercept the air leaving the trough 17 with a minimum of resistance. Moreover, the ribs 34 on one set of links in the upper run of the grate are disposed adjacent the air-spaces on the next transverse set of links so that a large number of narrow air-spaces are provided

through which the air is distributed in the form of fine sprays, and consequently it is thoroughly diffused throughout the fire. The construction of the links is clearly shown in Figures 3 to 7, inclusive, of the drawings. All the links are similar, with the exception that those between which the rollers 25 are mounted have the lugs 24 and portions of the ribs 34 cut away, as shown at 36 (see Figures 5 and 7), to accommodate the said rollers.

The air-troughs 17 are provided at their upper ends with inclined baffles 37 which connect the sides of said troughs and between which air-spaces are formed which slope upwardly towards the rear end of the furnace. These baffles are so arranged that the cross-sectional area of said air-spaces diminishes gradually towards the rear end of the furnace so as to regulate better the admission of air through the chain grate, less air being required at the rear end thereof owing to the fuel resting on that part of the grate being partially consumed and of less depth.

At the rear end of the grate a dumping-plate 38 is provided, which dumping-plate is pivotally mounted at 39 in brackets 40 on the air-ducts 10 and 11. The forward end of said plate rests on the upper walls 41 of the air-ducts 11 (see especially Figure 2) at a sufficient distance from the rear end of the troughs 17 to permit air therefrom to circulate on the under-side of said plate. It will be appreciated that fine ash can pass underneath the plate 38 into the ash-pit 42 below, and that clinker will pass over the plate into said ash-pit. A door 43 hinged to supports 44 in the furnace shell normally prevents the admission of air to the ash-pit 42 and is adapted to be opened by any convenient means, not shown, to permit clinker and ash to be removed periodically from said pit.

Rollers 45 mounted on spindles carried in suitable bearings in the lower ends of the inner walls of the air-ducts 10 are adapted to run on tracks 46 fixed to the shell 47 of the furnace, and from the foregoing description it will be apparent that the unitary frame-structure aforesaid comprising the air-ducts 10, 11, the transverse air-chamber 15 and the air-troughs 17, together with the chain grate and other parts mounted thereon, can be run out bodily from the furnace for cleaning or other purposes.

A fuel-hopper 48 is secured to the front wall 49 of the furnace, and said hopper is divided by a partition 50, arranged transversely with respect to the grate, into two compartments 51, 52. The partition 50 terminates a short distance from the chain grate and from the upper end of the hopper. The upper end of the partition 50 is connected to the front wall 49 of the furnace by a riddle

53 which slopes upwardly from said partition. The fuel is fed into said hopper so that it falls on to said riddle which permits the fine fuel to pass therethrough into the 5 compartment 52, while the coarse material falls into the compartment 51. Thus, it will be seen that the coarse material falls first on to the chain grate and subsequently the fine fuel falls on to the layer of coarse material, so that the possibility of fine material choking the air-passages between the links of the grate is minimized, if not entirely prevented.

10 At the rear of the compartment 51 of the hopper, an adjustable door 54, adapted to be actuated by any suitable mechanism in the usual manner is provided for regulating the depth of the fuel on the grate.

15 It is to be understood that the invention is not restricted to the precise constructional details described, as, obviously, various modifications can be made without departing therefrom.

I claim:—

20 1. A chain grate stoker of the type wherein the air for combustion is supplied under pressure, comprising in combination a frame-structure, an endless chain grate mounted thereon, an air-conduit extending substantially throughout the length of the grate in proximity thereto, which air-conduit is divided into two separate ducts arranged horizontally one above the other and in communication with one another at the rear end 25 of the grate, a transverse air-chamber at the front end of the grate in open communication with one of said ducts, means for admitting air into the other duct at the front end of the grate, and a longitudinally arranged air-trough in communication with said transverse chamber and disposed beneath the upper run of the grate.

25 2. In a chain grate stoker having an endless chain grate, the combination of a number of air-troughs arranged side-by-side beneath and in close proximity to the upper run of said grate, a plurality of inclined baffles connecting the upper ends of the sides of said air-troughs and spaced apart to provide air-spaces between them, which baffles slope upwardly towards the rear end of the troughs and are so arranged that the cross-sectional area of said air-spaces diminishes gradually towards the rear end of the grate, and means for admitting air for combustion into said troughs.

30 3. A chain grate stoker of the type wherein the air for combustion is supplied under pressure, comprising in combination an endless chain grate, an air-conduit having a flow, and return ducts, extending longitudinally along each side of the grate, a transverse air-chamber connecting said air-conduits, a number of longitudinally arranged air-troughs 35 leading from said air-chamber and disposed

beneath the upper run of the grate, an injector for admitting air to at least one of said air-conduits, and a number of steam-jets for inducing a flow of air through the said conduits and chamber into the air-troughs afore- 70 said.

4. In a chain grate stoker for a furnace, a chain grate mounted on a removable unitary frame-structure which comprises at each side of the grate flow and return air-ducts extending longitudinally of the grate and arranged horizontally one above the other, a transverse air-chamber at the front end of the furnace communicating with each of said return ducts, a number of air-troughs disposed longitudinally of and beneath the upper run of the grate in close proximity thereto, which troughs diminish in cross-sectional area towards their rear ends and at their front ends communicate with the transverse air-chamber, supports for said air-troughs carried by brackets on the inner walls of the air-ducts aforesaid, and inclined baffles connecting the upper ends of the sides of the air-troughs, which baffles are spaced apart to form air-spaces between them which slope upwardly towards the rear end of the furnace and are so arranged that the cross-sectional area of said air-spaces diminishes towards the rear 85 end of the furnace, a steam injector for inducing air into each of the flow ducts aforesaid, auxiliary steam jets arranged in the transverse air chamber adjacent the inlet openings to the said air-troughs, and a dumping-plate which rests at its forward end on the rear end of the frame-structure aforesaid and so as to permit air from said troughs to circulate on the underside of said plate.

5. The combination with a movable carriage, of a chain grate stoker mounted on said carriage, two longitudinal air-ducts one at each side of the chain grate and each having a wall forming a side wall for the latter, a transverse air-chamber communicating with said longitudinal air-ducts, at least one longitudinally arranged air-trough in communication with said transverse chamber and situated beneath the upper run of the grate, and means for producing a flow of air through said air-ducts and thence to the 100 grate, all constructed and arranged to form with said carriage a movable unitary structure.

6. In a chain grate stoker having an endless chain grate composed of a plurality of links which are interconnected by means of pins passing through said links, the combination with a frame-structure for carrying said chain grate, of two longitudinal air-ducts one extending along each side of the chain grate 105 and in close proximity thereto, a transverse air-chamber at one end of said grate communicating with said longitudinal air-ducts, a number of substantially U-shaped air-troughs disposed beneath and extending the 115

120

125

130

entire length of the upper run of the grate each of which air-troughs communicates with said air-chamber, and a number of rollers mounted on the pins aforesaid between adjacent links at intervals transversely of the grate and arranged to run on the upper edges of the sides of the air-troughs aforesaid.

7. A chain grate stoker as claimed in claim 3, in which one of said steam jets is associated with each longitudinal air-conduit, and a plurality of auxiliary jets are provided in said transverse chamber, one adjacent to the inlet end of each of the said air-troughs.

In testimony whereof I affix my signature.
